UNITED STATES PATENT OFFICE.

RAYMOND LEONARD BARTON, OF LOS ANGELES, CALIFORNIA.

DESIGN FOR A COMBINED WASHBOARD AND LAUNDRY TRAY.

Application filed June 7, 1928. Serial No. 27,032. Term of patent 14 years.

To all whom it may concern:

Be it known that I, RAYMOND L. BARTON, a citizen of the United States, residing at Los Angeles, in the county of Los Angeles and State of California, have invented a new, original, and ornamental Design for a Combined Washboard and Laundry Tray, of which the following is a specification, reference being had to the accompanying drawing, forming part thereof.

I claim:

The ornamental design for a combined washboard and laundry tray, substantially as shown.

RAYMOND LEONARD BARTON.
